(57) **CLAIM**

The ornamental design for an automobile dent repair device, as shown and described.

DESCRIPTION

FIG. 1 is a front, right, and top perspective view of an automobile dent repair device, showing my design.

FIG. 2 is a rear, left, and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is a partial enlarged view of an area labeled 9 in FIG. 1 comprising an adjusting knob; and,

FIG. 10 is a partial enlarged view of an area labeled 10 in FIG. 2 comprising a stand bar.

The broken lines shown in the drawings are included for the purpose of illustrating portions of the automobile dent repair device that form no part of the claimed design.
